UNITED STATES PATENT OFFICE.

ARTHUR A. VARDELL, DECEASED, LATE OF DALLAS, TEXAS, BY HIGHLAND GEE
VARDELL, EXECUTRIX, OF DALLAS, TEXAS.

MECHANISM FOR REMOVING USEFUL FIBER FROM SEEDS.

Application filed November 30, 1920. Serial No. 427,368.

To all whom it may concern:

Be it known that ARTHUR A. VARDELL, deceased, late a citizen of the United States, and resident of Dallas, in the county of Dallas and State of Texas, did invent new and useful Improvements in Mechanism for Removing Useful Fiber from Seeds, of which the following is a specification.

This invention relates to the general class 10 of machines adapted to remove fibers from their attachments, such as gins, cotton seed linters, wool-burring machines and the like.

Machines of this type are broadly alike, but for cotton the operation is customarily 15 carried out in two stages, the gin proper being relied upon to remove the long fibred cotton from the seed and the linter (or de-linter) gin being employed to work upon the cotton seed, which is the product of the 20 gin proper, to remove from the seed the short adherent fibers. The gin proper and the linter gin differ from each other essentially only in the adjustments, proportions or dimensions of the parts appropriate to 25 their specific duties. This invention has particular reference to means for the recovery of fiber or particles, applicable to saw gins for either use, and to other machines.

The invention will be illustrated and explained 30 in connection with a species of gin of the new type shown, described and claimed in the inventor's copending application Serial No. 319,105, filed August 22, 1919, Patent No. 1,426,687, of which this 35 application is a continuation in part.

All saw gins as heretofore constructed deliver a great volume of air as an incident 40 of the construction and operation of the doffing brush forming an essential part of the gin. This air, charged with fine particles of lint and dust, when delivered into the room, menaces the health and efficiency 45 of the operators, and constitutes a serious fire risk. Attempts have heretofore been made to minimize these risks by connecting the individual gins to deliver into a common conveyor, or by air-doffing the saws by separately generated blast or suction currents, or by other expedients, none of which are 50 wholly successful for this purpose.

In the best practise known in the prior art, 55 pneumatic doffing, or the common collection of fiber by delivery into a common flue or conveyor has resulted in unnecessary expenditure of power, often amounting to four

or more horse-power per gin. The rotating elements of the gin itself expend much power in moving with them a great volume of air.

When external pneumatic means heretofore have been employed the air-moving effort of the elements of the gin has been retained, with resultant waste of effort.

The present invention retains and utilizes the provisions of the said co-pending application for recovering a maximum percentage 60 of the separated fiber, for preventing escape of dust and particles of lint into the ginning room; for relating together the fiber-separating and doffing means in such a way as to secure a primary moting for the separation of heavier impurities prior to doffing the separating means; and for reducing the volume of air moved by the gin parts and employed to assist in the operations.

The present invention has for its further object the provision of means still further improving the purity of the delivered lint, such means being adapted to remove fine, light impurities or motes from all sources of collection of the lint; and to provide improved arrangements of the parts, including means capable of ready adjustment for controlling the delivery from the machine of the denuded seeds; for controlling the pneumatic currents where relied 80 upon to aid in separating out the impurities; and for relating together the improved ginning, doffing and moting elements to obtain the above and other benefits.

The machine comprises for these purposes means capable of acting on the lint torn from the seeds to separate the motes or impurities in accordance with the impact-velocity of the heavier particles; and other means operating in accordance with the 90 gravity-settlement of the remaining impurities against flotation in a gentle air current. These means may act successively or severally at different times, and one object of the invention is to provide in a gin having 95 the essential saws or other fiber-separator means and the essential doffer means, devices for acting on the product a number of times thoroughly to separate the motes from the good lint. In the preferred form, there 100 are two mote-separating stages in the operation, in one of which motes and fiber are separated primarily according to their different impact-velocities, and in the other of which the separation is effected primarily 105 110

according to the different rate of settlement under gravity of motes and fiber in an air-current.

In the accompanying drawings illustrating 5 one preferred form of the invention,

Fig. 1 is a vertical central section through a linter gin embodying the invention; and

Fig. 2 is a detail from elevation partly in vertical section on the line 2—2 of Fig. 1, 10 showing means for one of the adjustments.

Referring to the drawings, Figure 1 best shows the arrangements of the new type of gin in which the fiber separator element comprises a cylinder of saws 10 built up on 15 the shaft 2, arranged to be driven as usual in adjustable bearings, not shown, on the frame 1. Behind and beneath shaft 2 a rotary doffer brush 5 of smaller size than usual is arranged to operate with the creation of as little air current as possible, for instance as explained in the said Patent No. 1,426,687, the brush cylinder preferably being of the construction described and claimed in the divisional application Serial No. 429-, 20 562 filed of even date herewith (Patent No. 1,426,689). For the purpose of adjustment to take up wear and other purposes the shaft 3 of the doffer brush is arranged for at least vertical adjustment; for instance by means 25 of the screws 46, 47 in frame lugs and respectively bearing on and clamping movable bearings 48 for shaft 3. The brush lies preferably at a position at which its center of rotation is in a plane extending downwardly 30 about 20° and to the rear of the vertical through the center of rotation of the saw cylinder 2, 10; but a variation fore and aft of several degrees will still accomplish the purposes intended for this position of the 35 brush. Among these purposes are capacity for ready access to the brush without removing the saw-cylinder; capacity to employ the brush-created air-currents for a suction effect countervailing the air-blast from the 40 saws, and active as far upward and forward as the gin-grate and seed-gate; capacity to mote above the brush and behind the saws; and capacity to utilize the action of the brush 45 for moting according to a different method 50 in the region under the brush; and capacity to obtain a delicate adjustment of the effect of air-currents in the gin or simple changes in the position of its static parts.

The saw cylinder cooperates, as usual, 55 with the ribs 9 of a gin grate which may be of any preferred or usual construction, and beyond the grate the saws, as usual, run in contact with a roll or rotating mass of material to be ginned rotating in the roll box generally designated at 8, which has improved features presently explained. The charge in the roll box may be replenished by any usual or preferred type of feeder 12, 13 appropriately associated with the frame 1.

65 The mentioned arrangement, dimensions

and operative capacities of the doffer brush 5 are such as to provide spaces exposing a wide arc of the periphery of the saws behind the saws and above the brush and below the saws and in front of the brush. These 70 spaces are utilized in the manner hereinafter described, respectively as a primary moting chamber A and as a receiving space B for doffed lint centrifugally thrown from the saws and the brush 5.

75 A space G beneath the brush 5 is also made available for a secondary moting operation.

To permit these operations the gin comprises a back seal 26 enclosing chamber A, 80 for instance connecting the frame longitudinal 1° and the top of a vertical back board 27 which is provided with an adjustable air gap 32, and preferably with an interior baffle 33 for distributing a current of air 85 entering through the gap 32. On frame longitudinal 21, and preferably hinged thereto at 22, an adjustable mote blade 20 is adapted to be fastened by the thumb nut 23 with its point 24 in a predetermined position, which further defines the chamber A. The bottom of the chamber A may be closed by a trough member 29 from which a screw conveyor 30 can remove the motes.

The rear side of the brush 5 works in 95 close proximity to a sealing concave 37, preferably hinged at 38 and adjustable by a thumb nut 39.

One face of the concave 37 also defines the upper side of a flat suction trunk 50, of 100 which the lower side terminates at a line 51 spaced from the periphery of the brush 5. The suction trunk 50 may be supported by a suitable frame member 52. A continuous suction of predetermined pressure is provided in trunk 50 by means, not shown, exterior to the machine. The bottom wall of the suction trunk is continued, in adjustable direction and position, by a mote board 55 preferably hinged at the line 51 and having means, such for instance, as the sector 56 and lock nut 57, for adjusting the angular position of the mote board 55 about the line 51.

The space or chamber B in front of the 115 brush 5 is closed by an adjustable wall serving as an air deflector and air current velocity-controller. This structure preferably comprises three parts, an inclined board 70 preferably having a metallic lining 71, 120 and flanges 72 horizontally slotted at 73 for adjustment by hold-down screws 74; a vertical board 75 between the lower edge of the board 70 and the floor under the gin, having a flange 76 and similarly capable 125 of adjustment; and a seed slide and air-regulator 78. The upper left hand side of the board 70 provides support, for instance, for an adjustable preferably metallic, structure 77 having the inclined face 78 approxi- 130

mately radial to the saws to guide the seed falling out of the roll box and breast-structure, and adjustably to determine the clearance between its inner edge and the saw peripheries. The margins of the structure 77 are preferably arranged to be pinched by pinch screw 79 in the slot 80 in the part 70 for adjustment purposes.

By these arrangements the position of the inclined slide and air deflector 78, of its inner margin, and of inclined wall 70 may be horizontally shifted to change the width respectively of the clearance at the saws and of the throat 81 between the periphery of the brush 5 and the inner face of the board 70, and hence to control the air-current flowing downwardly in this space as a result of the motion of the saws 10 and the brush 5, which is also somewhat affected by the inflow into the suction trunk 50. The relatively feeble blast effect of the brush 5 is herein concentrated at 81 to a maximum velocity of flow.

The relative positions of the front board 75 and the mote board 55 together control the extent and operation of an air gap G lying beneath the brush 5, and provide means for a secondary moting of the lint before delivery. The current flowing down the passage 81 is directed toward the center of gap G by its surroundings. The current induced by suction trunk 50 and flowing in the direction of the arrows α from behind and beneath the gin flows upwardly into this gap, predominantly along the front wall 75. The current flowing into the suction trunk 50 flows about the periphery of the brush and across the top of this gap and some of it is diverted downwardly along the wall of the gap defined by the mote board 55.

The effect of this is to maintain a gentle upward current in the gap G, in which there is a central cyclonic eddy as illustrated at e resembling the effect secured by the machine of the inventor's prior Patent No. 1,102,177, June 30, 1914. So much of the product generally of the gin flowing through the passage 81 as contains any motes is appreciably detained in the gap G during a sufficient time to permit fine light motes flowing with the product stream to settle by gravity out of the stream entering the suction trunk 50. This action is aided by the tendency of the pure lint to follow the periphery of the brush and enter the trunk 50 without participating in the eddy e , and by the velocity of the whirl e in aid of gravity to separate out particles slightly heavier than the lint.

The action of the gin-elements proper of the machine will now be clearly understood. Primary moting is effected in the chamber A as explained in the said parent application. The peripheries of the saws 10 leaving the grate 9 impart a great impact ve-

locity to the heavier and more solid impurities such as concretions of lint, sand, scraps of boll, pieces of stick and fragments of broken seed. These motes are thrown in the direction of the arrows γ under this impact 70 velocity and pass to the right of the point 24 of the mote blade 20. The greater part of the lint travels in the teeth of and near the peripheries of the saws 10. Such of it as may have accompanied the motes thrown in 75 the direction γ is returned to the saws by the indraft of air flowing through the gap 32, as induced by the rotary fan action of the saw cylinder and the brush 5, there being no free path for air past the concave 37 and 80 the support 21 for the mote blade 20. The action in the chamber A is therefore a centrifugal impact-velocity separation of the heavier particles, coupled with the pneumatic return to travel with the saws of the 85 finer and lighter part of the lint. Some impurities desirable to be removed which are very slightly heavier than the lint are also returned to the saws when the adjustment of the air gap 32 and the remaining adjust- 90 able parts is that desired.

As also explained in said parent application, the inflow into the space beneath the grate and the saw cylinder and up the slope 78 is relied upon to recover and to take into 95 the pneumatic currents flowing in the gin that portion of lint which is actually separated by the saws but left in the roll box or in association with the seed falling away from the grate 9.

This fraction of the lint often contains motes of a light nature, which do not enter the chamber A at all, and may contain immature seed, pieces of hull and other matters mixed with the charge which fall out 105 of the incoming charge of seed from the feeder on the first half of their travel with the roll in box 8. Motes from this source are also effectively separated from the lint in the gap G.

Brush 5 doffs the saws peripherally according to the operation explained in said parent application, by the action of the annular series of bristles mechanically sweeping the peripheries and the faces of the saws 115 near the teeth, and throws fiber off into the chamber B above the board 70. By these arrangements all the fiber is mixed thoroughly with the air with little or no formation of a mat on the doffer brush 5, and the 120 stream of fiber laden air is in condition to be subjected to the gravity-and-cyclone separation action taking place in the gap G. The result of the operation is to deliver through the trunk 50 lint in a state of purity 125 not attained heretofore by any means of which the subscriber is aware.

The operation of the gin especially when its dimensions and adjustments are, as shown, those for delinting, is further aided 130

by improved devices associated with the roll box 8 for retaining the unginned seeds in contact with the saws until they are thoroughly delinted. Efficient action to this end 5 has heretofore been sought in the operation of linters, but has been attained with difficulty by skilled persons, and has not been in convenient reach of the average operator for lack of appropriate means to adjust the 10 old parts of the machine.

The preferred construction of the breast structure comprises the usual grate-fall 9, 11, pivoted at 90, and preferably in the present case comprising an upper longitudinal 15 channel member 16 adapted to be locked by the shackle-bolts 17 to the ends of the frame longitudinal 1°. The usual driven float 6 is journaled in the end plates 8^a of the breast-structure or roll box 8, and the usual hopper 20 per 18 may be provided by a forward bend of a metallic lining 100 suitably fastened to the interior of a grid casting 101 defining the front wall of the roll box and pivoted on the end pivot screws 102 in suitable bores 25 in the casting 101, see Fig. 2, for limited motion of the seed board, so called, (the front wall 100), about the point of the axis 102 as a center. The lower end of the frame 101 terminates in a rake-head 103 and in the 30 hinged front cover 104. The rake-head 103 has the important function of determining the degree of contact with the saws of seeds otherwise free to drop out of the roll box 8 by gravity, by positioning these seeds in 35 respect to the rotating saws to determine whether they will be seized by the saws and again taken around with the roll, or whether they will drop through the slots in the rake-head and fall out of the machine. The de- 40 sired automatic action is such as to detain in the roll any seed with enough projecting fiber on it to be influenced at all by the near proximity of the saws. To obtain this effect, axial and radial adjustment of the rake- 45 head 103 with respect to the axis 2 of the saw cylinder is essential. This is effected by permitting longitudinal motion in the direction of the axis 2 at the pivots 102 to the minute degree necessary, and by effecting the 50 radial adjustment of the rake-head 103 accurately and evenly from side to side of the gin.

For these purposes the pivot screws 102 may be coincidentally moved to shift the 55 whole frame 101 axially through the clearance between it and the heads 8^a for the minute adjustment necessary. Rotation of the structure 101, 103 about the centers 102 is relied upon for the adjustment toward and 60 away from the saws, and is controlled by an eccentric shaft or rod 110 bearing in yokes 111 of the ribs 112 of the frame 101, the eccentric shaft 110 being held to freedom for a substantially radial motion only in respect 65 to the centers 102 by yoke covers 113 fastened

to the yokes 111. The rotary position of the shaft 110 is held by a lock nut 115 on the threaded and reduced end 116 of the shaft 110. This reduced end 116 is journaled in a threaded gland 117 having a shoulder 118 70 and a locking hand-nut 110 adapted to pinch the gland 117 in ways 118 substantially radial to the center 2 and formed in the heads 8^a of the roll-box.

These arrangements are such, it will be 75 observed, as to permit the shaft 110 and the frame 112 to be swung upwardly freely about the pivots 102 as a center, upon releasing the glands 117 from the slots 118. When locked in place the glands 117 permit 80 delicate adjustment of the rake-head by turning the shaft 110 and locking it by means of the lock nuts 115. It will be understood that the shaft 110 is provided with spanner-holes 120 for an implement for turning it, and that 85 the structures as shown at the left of Fig. 2 are repeated at the right in a symmetrical sense.

What I claim is:

1. Mechanism for removing useful fiber 90 from seeds having therein rotary means for tearing the fiber from the seeds, primary means for separating motes, thrown centrifugally outward from said rotary means, from the fiber, means for delivering the 95 separated fiber from the machine, and secondary means comprising an open air gap for separating motes from the fiber on its way to said delivering means.

2. Mechanism for removing useful fiber 100 from seeds having therein means for separating the fiber from the seeds, means for separating motes from the separated fiber according to the different impact-velocities 105 of the fibers and the motes, means for collecting the separated fibers in a stream for delivery from the mechanism, and means comprising an open air gap across which said stream passes for separating motes from the fibers according to their different specific 110 gravities.

3. Mechanism for removing useful fiber from seeds having therein rotary saws for tearing the fiber from the seeds, primary means for separating motes, thrown centrifugally outward from the saw, from the fiber, pneumatic means for delivering the 135 separated fiber from the machine, and secondary means comprising an air gap through which flows an upwardly directed air current for separating motes from the fiber.

4. A saw gin having therein moting means adapted to separate particles thrown by impact of the saw teeth from material traveling with the saws, doffer means for the saws, and means comprising an open air gap over 125 which the doffed material is caused to pass for separating the heavier from the lighter parts of the material.

5. A saw gin having therein moting means 130

- adapted to separate particles centrifugally thrown by impact of the saw teeth from material traveling with the saws, pneumatic means for hindering centrifugal motion of the material traveling with the saws, doffer means for the saws, and means cooperating with the doffed material for separating the heavier from the lighter parts of the material.
- 10 6. A gin having therein rotary means for tearing the fiber from a mass of seeds, means for separating the fiber from impurities centrifugally thrown from said rotary means, means for doffing the fiber from the rotary means, means for collecting detached fiber from the seeds and means for subjecting the doffed and detached fiber to the action of a gentle upward current of air for moting such fiber by gravity action.
- 20 7. In a gin, in combination with a series of rotary saws and a rotary doffer-brush, means for moting the saw-detached fiber having a part for separating the paths taken under impact of the saws by motes and by good fiber, and means for moting the fiber separated by the saws having therein means for exposing the air-stream containing the fiber and induced by the doffer brush to the action of gravity in the presence of an entering air-stream moving upward.
- 30 8. A gin having therein rotary means for tearing the fiber from the seeds, means for separating the fiber from impurities centrifugally thrown from said rotary means, means for doffing the fiber from the rotary means, means for moting the doffed fiber by the action of gravity, and pneumatic means for removing the cleaned fiber from the machine.
- 40 9. A gin having therein rotary means for tearing the fiber from the seeds, means for separating the fiber from impurities centrifugally thrown from said rotary means, means for doffing the fiber from the rotary means, means for moting the doffed fiber, comprising an open chamber wherein the fiber is subjected to the action of gravity in a gentle upward current of air and a suction flue for removing the fiber from said last mentioned moting means.
- 50 10. A gin having therein a grate and rotary saws beneath and behind the grate, and a rotary brush coacting with the saws at an osculating line beneath and behind the saws, in combination with horizontally adjustable air-deflector means closing the space in front of the brush, said means being removable to permit access to the brush without disturbing the grate or saws.
- 60 11. A gin having therein, a grate and rotary saws beneath and behind the grate, and a rotary brush coacting with the saws at an osculating line beneath and behind the saws, in combination with a substantially vertical plate having an upwardly and forwardly di- rected extension, and means for removably securing said plate in operative position, said plate with its extension defining, a space for doffed lint in front of the brush and coacting with the brush to establish an inward air current at and beneath the forward edge of the grate.
- 70 12. A gin having therein, a grate and rotary saws beneath and behind the grate, and a rotary brush coacting with the saws at an osculating line beneath and behind the saws, in combination with moting means above the brush and behind the saws, means enclosing the front of the brush to form a doffed-fiber reception space and adapted to direct air moved by the brush downwardly and to the rear of the brush, and a pneumatic trunk behind the brush, the parts providing an open gap directly below the brush for the entrance of air and separation of motes.
- 80 13. A gin having therein, a grate and rotary saws beneath and behind the grate, in combination with a rotary brush coacting with the saws at an osculating line beneath and behind the saws, and with moting means above the brush and behind the saws, means enclosing the front of the brush to form a doffed-fiber reception space and adapted to direct air moved by the brush downwardly and to the rear of the brush, and a pneumatic trunk behind the brush, the parts providing an open gap under the brush for the entrance of air and separation of motes.
- 90 14. A gin having therein a grate and saws rotating on an axis behind and beneath the grate, and having a doffer brush rotating on an axis beneath and slightly behind the vertical from said saw axis, in combination with an adjustable air deflector beneath the grate and in front of the brush and saws adapted to cooperate with the brush to draw air over the deflector and into a space in front of and beneath the brush, said air deflector being bodily adjustable toward and from the vertical plane of the axis of the brush whereby to vary the width of the space in front of the brush.
- 100 15. A gin having therein a grate and saws rotating on an axis behind and beneath the grate, and having a doffer brush rotating on an axis beneath and slightly behind the vertical from said saw axis, in combination with an adjustable air deflector beneath the grate and in front of the brush and saws adapted to cooperate with the brush to draw air over the deflector and into a space in front of and beneath the brush, an adjustable mote-board spaced from said air-deflector and beneath and behind the brush, and a lint-trunk having an intake between the mote-board and the brush.
- 110 16. A gin having therein a grate and saws rotating on an axis behind and beneath the grate, and having a doffer brush rotating on an axis beneath and slightly behind the ver-
- 105 115 120 125 130

tical from said saw axis, in combination with sealing means in proximity to the rear of the brush for substantially preventing upward passage of air currents induced by its motion, a moving chamber above said sealing means, a suction flue having an intake beneath said sealing means, an air-deflector in front of the brush for directing the doffed fiber and air moved by the brush downward-

ly and rearwardly, and an adjustable motor board under the flue-entrance adapted to regulate a moving air-gap under the brush and behind the air-deflector. 10

Signed by me at Dallas, Texas, this 10th day of November, 1920.

HIGHLAND GEE VARDELL,
*Executrix of the last will and testament of
Arthur A. Vardell, deceased.*
